UNITED STATES PATENT OFFICE.

FREDERICK COATES, OF ROCHESTER, NEW YORK.

LABELING, FILLING, AND STOPPERING MACHINE.

1,211,289.

Specification of Letters Patent.

Patented Jan. 2, 1917.

Application filed January 2, 1913. Serial No. 739,800.

To all whom it may concern:

Be it known that I, FREDERICK COATES, of Rochester, in the county of Monroe and State of New York, have invented certain new and useful Improvements in Labeling, 5 Filling, and Stoppering Machines, of which the following is a specification.

My invention relates to apparatus for the labeling, filling and stoppering of bottles or 10 other containers or packages, the term "bottle" as also the term "label" being used herein in an illustrative and not in a re-strictive sense.

One of the prime objects of the invention 15 is to provide a unitary organization having co-operative parts relatively arranged and connected for handling a bottle by a continuous series of timed operations to apply a label or the like at one stage of 20 operative handling, to deliver material to the bottle at another stage, and to apply a stopper or other closure element at another stage. In carrying out my invention for these ends I preferably provide an organization 25 wherein the same operative elements to a large extent are arranged to perform or control a plurality of the described operations so that the number of operative parts and connections required is reduced to 30 a minimum with the operating parts of an especially simple character, and this interconnected arrangement also providing a relatively timed movement of parts whereby the several operating devices move in 35 synchronism and the bottles are labeled and filled with great celerity.

In the concrete embodiment of the invention to be described for illustrative purposes the labeling mechanism is arranged to 40 handle the bottles before the filling and stoppering thereof and I have chosen as a suitable form of labeling mechanism to illustrate for use as a part of the combinations comprising the invention, one of the 45 general type shown in my Patent No. 1,049,996, issued January 7, 1913.

The above and other objects and features of the invention will be better understood from the following detailed description 50 taken in connection with the accompanying drawings and will be thereafter pointed out in the appended claims.

Referring to the drawings, Figure 1 is a side elevation of a preferred embodiment of 55 the invention with parts in section; Fig. 2 is a detail sectional view showing the stop-

per holding device; Fig. 3 is a plan view of the machine; Fig. 4 is a detail elevation of the pump; and Fig. 5 is a fragmentary vertical section showing the pump controlling 60 valve.

The operating parts are shown as mounted on a stand or table 1 supported at a suitable height by legs 2. This stand has at one end journal bearings 3 for a prime driving 65 shaft 4; the stand is also provided at an intermediate point with a vertical stud 5 affording journal bearing for a rotating table or turret 6 which transfers the bottles to filling and stoppering stations, and 70 near its end opposite from the shaft 4 the stand has a vertical post 7 extending up some distance to afford journal bearing for a rotating table 8 which constitutes an essential part of the labeling mechanism. 75 Since in the embodiment shown the first operation is the affixing of the labels to the bottles, the labeling mechanism will be first described, such mechanism being shown in sufficient detail for purposes of the present 80 case, and reference being had to my aforesaid patent for a more complete understanding thereof. The rotating table 8 has a depending sleeve 9 fitted around post 7 which holds the table at some little elevation as shown, the lower end of this sleeve carrying a gear 10 which is driven through an intermediate 11 from a gear 12 rigid with the turret 6, the turret 6 and table 8 being thus geared together and having common 85 step-by-step movements imparted thereto. As a suitable means for imparting this intermittent movement the gear 12 has on its top face a series of pins 13 engageable by a forked extremity 14 of a pawl 90 arm 15 pivotally carried at 16 by a slide block 17 fitted in ways on the bed frame, the slide block 17 in turn, being reciprocated by a bell crank lever 18 pivoted to a pedestal on the frame work at 19 and having 95 a roll 20 engageable in a cam groove 21 of a cam wheel 22 fixed on shaft 4. The pawl arm 15 is shown as of a construction whereby while its end is engaging one of the pins 13, an intermediate portion bears 100 against the next pin as seen at 23 to lock the turret from further rotation until the pawl arm is withdrawn. The table 8 is formed with a series, shown as 4, of cut out radial slide ways 24 in which are fitted 110 forked slide carriers 25 which are arranged for positive in-and-out movement on the

table at different parts of its rotation by having roller pins 26 at the inner end of each slide carrier working in a cam groove 27 formed in the lower face of a cam plate 28 stationarily clamped as seen at 29 at the 5 top of post 7. The forks of carriers 25 are spaced apart far enough to permit a bottle or other container of the maximum size to be handled by the machine, to be 10 pressed therethrough, and each of these 15 forks is equipped with a yielding inwardly extending seat portion as seen at 30 on which the bottles are adapted to be placed, the flaps composing these yielding seat portions being stiff enough to hold the weight 20 of the bottles but yielding to permit them to be pressed down past them.

By reference to Fig. 3 it will be seen that 25 the cam groove 27 is so formed that at stations *a* and *b* the slide carriers are projected outward and at a suitable point, as shown between the stations, a glue applying device shown as equipped with a roll 31, is mounted in position so that said roll will 30 apply glue or like adhesive to the outwardly projecting lower faces of the slide carrier forks which are formed with flat platen surfaces 32 to receive the adhesive. At the station *b* to which the carriers progress after having their lower platen faces thus 35 covered with adhesive, a label holder 33 is mounted for vertical movement, this holder being adapted to hold a stack of labels and having a downward extending post 34 vertically guided in a column 35. The label 40 holder post 34 has connection with an operating bell crank lever 36 pivoted at 37 to the bed, this connection being yielding in an upward direction by means of a spring 38 fitted around post 34 and against a shoulder 45 thereof at its top, with a slip collar 39 at its bottom. The bell crank lever 36 is operated through a link bar 40 and a lever 41 fulcrumed at 42, by a roller pin 43 in a cam slot of cam wheel 22, to move the label 50 holder up each time a carrier 25 is positioned thereover, to press the topmost label against the adhesive covered platen surfaces of the carrier forks to which it adheres as 55 the label holder with the rest of the stack of labels is lowered. At the next step movement of the table the forked carrier with a label thus adhering to the platen surfaces 32 and with a bottle on the seat flaps 30,— 60 the bottle having been deposited either at station *a* or station *b*—is moved around to station *c* where it is drawn in toward the center of the table by the portion 27' of cam path 27 and the bottle with the label 65 stretched between the carrier forks beneath the same is now positioned below a presser head 44 carried by a horizontal arm 45 which is moved vertically as later described, and a yielding backing block 46 beneath, this backing block having a depending bar

47 slidably guided in a sleeve mounting 48. The construction of this backing block which is yieldingly held upward by a spring until it is pressed downward when it is held down by a latch 47', with a cam piece 47" in position to trip said latch at the 70 proper point, is more fully set forth in my aforesaid patent, and I also refer to said patent to further show the construction of wiper brushes 49 which engage the label 75 ends while the middle of the label is gripped against the bottle by the backing block 46 to smooth the label extremities about the bottle as the bottle is pressed from its seat by the presser head 44 moving downward and depressing the block 46. The bottle 80 thus resting on the backing blocks 46 in its depressed position as held down by the latch 47', the bottle being below the plane 85 of the table, is moved from station *c* to station *d* where it is pressed endwise outward into a chute 50 held on a bracket 51 and having a horizontal receiving portion merging by a curved contour into a vertical delivery portion, down which the bottles slide. 90 As a suitable means for pressing the bottles thus endwise outward from their seats on the blocks 46 into the chute 50 I provide a presser piece 52 carried at the end of a lever arm 53 pivoted at 54 in the base and 95 having a lower extension pivotally engaged at 55 with the bar 40 so that this push out device and the label holder have a common actuator.

The turret 6 is provided with a series 100 shown as 8 of bottle receiving pockets 56, these pockets being so arranged and the gear connections between the turret 6 and table 8 being so proportioned that with each 105 step movement which the turret and table receive from their common actuator, one of the pockets 56 is positioned directly beneath the chute 50 to receive the bottle in upright position therefrom. The next step movement of the turret transfers the bottle to a filling 110 station *e*, the side of the chute being cut away as seen at 57, to permit this bottle transfer. The open top of the bottle is now 115 positioned adjacent to and directly beneath the discharge outlet 58 of a vertically arranged pump 59, the piston rod 60 whereof has adjustable nuts 61 engageable by a block 62 at the upper end of an upright bar 63 vertically guided in ways on the frame work. The top of bar 63 also has fixed thereto the horizontal arm 45 which operates the presser head 44 so that said head and the pump plunger move together while the respective bottles beneath the same are at rest. The block 62 has frictional sliding engagement as indicated at 64 with a slotted link bar 65 which by a pivotal connection 66 controls the turning plug valve 67 alternately opening the inlet passage 68 and closing the discharge passage 69 and 120 125 130

vice versa. The proper amount of turning movement of the valve plug is determined by a stop device 70 the excess movement of block 62 being permitted by the frictional connection 64, and the correct amount of pump piston movement for the desired discharge being determined by adjustment of the nuts 61. The bar 63 is moved up and down at proper timed intervals for performing its dual functions by having a pivotal engagement at 71 with a lever 72 pivoted to the frame work at 73 and having a roll pin 74 engaging a cam slot in the cam wheel 22. The bottles after being filled are at the next stage of turret movement moved to station 7 where the stoppers or other closures are applied. For this purpose I provide a vertically moving plunger 75 guided in the pedestal 76 and having pivoted link connection as at 77, 78 with an operating lever 79 shown as pivoted on the same axis 19 as the lever 18 and having a roll 80 engaging a still further cam slot in the cam wheel 22. As a suitable means for holding the stoppers in position to be pressed by the plunger 75 into the bottle neck, I show a bracket arm 81 extending from the pedestal support 76 with a conical seat 82 to receive the stopper and a passage 83 therefrom for the cork a slightly smaller than the neck of the bottle so that as the bottom of this passage is positioned closely above the top of the bottle the cork is compressed in passing therethrough and is thus easily guided into and fitted to place in the bottle neck before it has an opportunity to expand to normal size.

While I show herein only this single stoppering device, in certain aspects of the invention I intend this to typify any suitable closure applying means, whether single for merely applying stoppers or multiple as for applying stoppers, tin foil caps and the like, and I therefore desire this element to be understood as merely illustrative in the combinations to be set forth. After the filled bottles are thus stoppered by the properly timed operation of the plunger 75 they are at the next step in the rotation of the turret brought into engagement with a discharging device which as shown consists in an arm 84 having a curved extremity extending over one side of the turret in position to move the bottle out of the pocket 56 on to any suitable receiving platform. It is to be observed that the bottles are thus automatically handled by a continuous sequence of operations, for the labeling, filling and stoppering thereof without manual intervention from the time they are placed on the table carriers of the labeling mechanism until they are discharged from the holding pockets on the turret of the filling mechanism. Further the described organi-

zation is one of maximum simplicity and effectiveness by reason of the fact that the intergeared and interconnected relation of parts in the entire machine reduces to a minimum the operative connections required, while insuring that the several cooperative parts of the machine shall operate in precisely timed relation, so that the operating movements of labeling, filling and stoppering can all take place simultaneously during the dwells between the step movements of the intergeared labeling table, and filling turret as effected by the operation of their common pawl arm actuator. The delivery of the bottles from the labeling mechanism to the filling turret is substantially a positive and definitely timed one, for, though the bottles are guided down the chute partly under the influence of gravity, they are also pushed positively through the chute by the pusher bar which as it pushes one bottle into the chute, causes it to press against the bottle ahead of it if it should remain in the chute, to insure its ejection therefrom into the turret pocket.

While I have herein shown what I now consider to be a preferred embodiment of the invention I am aware that numerous changes in details of construction and arrangements of parts can be made without departing from the essential attributes of the invention and I therefore do not desire to be limited to the present, or any specific embodiment of the invention but refer to the appended claims rather than to the foregoing description to indicate the scope thereof.

Having described my invention what I claim as new and desire to secure by Letters Patent is:

1. A machine of the kind described, comprising label applying mechanism, consisting in a rotatable turret adapted to receive bottles flatwise with means associated therewith for supplying labels and adhesive and fitting the labels to the bottles, filling and stoppering mechanism having a turret adapted to receive the bottles standing up, and means for transferring the labeled bottles to said second turret, said means consisting in a chute having a horizontally extending receiving portion and a vertically extending delivery portion to deliver bottles upright on to seats of said second turret whereby the bottles are positioned for filling and stoppering on the second turret.

2. A machine of the kind described, comprising a carrier adapted to receive bottles flatwise and having means associated therewith for supplying labels and adhesive to the bottles at successive stations, a second carrier having means associated therewith for filling and stoppering the bottles, and transfer means having provision for positive actuation to deliver the bottles from hori-

zontal position on the first named carrier to upright position on the second carrier, said carriers being intergeared for definitely timed step-by-step movement.

- 5 3. A machine of the kind described, comprising a carrier adapted to receive bottles flatwise and having means associated therewith for labeling the bottles, a second carrier having means associated therewith for filling the bottles, and a transfer device for shifting the bottles from the first named carrier to the second carrier equipped with a positively actuated pusher for initiating the bottle transfer, said device having a 10 chute way terminating in a vertically extending portion adapted to deliver the bottles upright to said second carrier.

4. A machine of the kind described, comprising two turrets intergeared for step-by-step rotation, one at a higher elevation than 20 the other, one of said turrets having means associated therewith for labeling the bottles, the other turret having means associated therewith for filling the bottles, there being 25 a transfer chute between said turrets adapted to receive the bottles flatwise from the higher turret and having a vertically extending delivery portion to discharge the bottles upright on to the lower turret.

- 30 5. A machine of the kind described, comprising a horizontally disposed turret having means associated therewith for labeling bottles, a second turret at a substantially lower elevation having means associated therewith for filling the bottles, said turrets being intergeared for definitely timed step-by-step rotation, a curved transfer chute adapted to receive the horizontally disposed bottles on the first named turret and terminating in a vertically extending portion in 35 position to deliver the bottles upright to the lower turret, and a positive pusher connect-

ed for movement to initiate the bottle transfer from one turret to the other.

6. A machine of the kind described, comprising a turret mounted for rotation, bearing a series of carriers adapted to receive bottles flatwise in horizontal position, means coöperative with said turret for supplying and affixing labels to bottles on said carriers, a second turret having seats for receiving bottles in upright position, and with bottle filling means coöperative therewith, means for moving said turrets in timed relation with a step-by-step movement and 55 means for automatically transferring bottles from the first turret to the second turret during dwells between turret movements.

7. A machine of the kind described, comprising a turret mounted for rotation bearing forked bottle carriers to receive bottles flatwise, with provision for in-and-out movement on the turret, label and adhesive supplying and label affixing means mounted in coöperative relation to bottles on said carriers, a second turret at a lower elevation having seats for receiving bottles upright, means for transferring bottles from said carriers to said seats, bottle filling means and bottle stoppering means mounted in coöperative relation to bottles carried by said second turret, said two turrets being in geared connection, and a common actuating means having connections to impart step-by-step movement of said turrets and other 75 connections to actuate said label applying, said bottle filling, and said stoppering means during dwells between turret movements.

In testimony whereof I have affixed my signature, in presence of two witnesses.

FREDERICK COATES.
